UNITED STATES PATENT OFFICE.

WILLIAM S. SMOOT, OF ILION, NEW YORK, ASSIGNOR OF ONE-HALF HIS
RIGHT TO E. REMINGTON & SONS, OF SAME PLACE.

IMPROVEMENT IN CARTRIDGES FOR FIRE-ARMS.

Specification forming part of Letters Patent No. 152,428, dated June 23, 1874; application filed
July 5, 1873.

To all whom it may concern:

Be it known that I, WILLIAM S. SMOOT, of Ilion, in the county of Herkimer and State of New York, have invented certain Improvements in Cartridges, of which the following is a specification:

My invention relates to metallic cartridges; and the invention consists in a peculiar manner of re-enforcing the head, of securing the anvil in place, and in combining a cylindrical shell with a taper chamber of a gun, all as hereinafter explained.

Figure 1 is a longitudinal section of the chambered portion of a gun-barrel with the cartridge inserted. Fig. 2 is a longitudinal section of my cartridge as adapted to military arms or rifles; Fig. 3, a similar view of the same as prepared for use in shot-guns; and Fig. 4 is a sectional portion of the head, illustrating the manner of securing the anvil therein.

In constructing my cartridge, I draw up the shell B, of metal, in the usual manner. I then place within the head a disk or wad, b, having a hole in the center, of such a size as to permit the disk to fit down within the head around the battery-cup or recess c made in the center of the head, this cup or recess being formed by pressing in the metal at the center of the base or head, in a manner well known at the present day, and as shown in Figs. 2, 3, and 4. I then provide a cup, a, and insert it within the shell B, and then, by means of a die and press, subject the cup and head, with the disk, to a heavy pressure, whereby the parts are pressed very closely and firmly together, thus causing the disk to expand laterally and perfectly fill the cavity of the head between the outer walls of the shell and the sides of the battery-cup c. This disk I make either of soft metal or of paper suitably prepared, so that when subjected to the pressure it will remain set or fixed, its object being to act as a re-enforce to strengthen the head of the cartridge. The cup a is intended not as a means of re-enforcing the head, the wad or disk b doing that, but as a gas-check, to prevent the gas from entering any crevice in the head, and it may be made of comparatively light metal.

In Fig. 3 I have shown this cup a as extending the entire length of the shell, by which

means I am enabled to use a cheaper metal, such as zinc, for the outer shell B.

In constructing my cartridge, whether it be reduced in diameter at the front, as represented in Figs. 1 and 2, or made of uniform diameter throughout, as in Fig. 3, I make the body cylindrical—that is, it is not tapered at all, except where "necked" or reduced in diameter, which is only done when intended to be used in rifles or military arms. The chamber of the arm in which they are to be used I taper, as represented in Fig. 1, its diameter at the rear being increased from two to four thousandths of an inch, this being exaggerated in the drawing for the purpose of illustrating the idea. The front end of the cartridge should be made to fit the chamber at the front as closely as possible when inserted, to prevent the gas from entering between the outside of the cartridge and the walls of the chamber.

When the cartridge and chamber of the gun are thus constructed, it will be seen that there is little or no possibility of the escape of gas when the gun is fired, the cartridge fitting snugly at its front end, while the elasticity of the metal composing the shell allows it to expand under the pressure of the charge sufficiently to cause its body to come in contact with the walls of the chamber of the gun, and to contract again when relieved from the pressure of the gas. It will also be seen that when thus constructed the shell, although forced in tight, will be relieved or rendered loose, as soon as it is moved a very little from its seat in the chamber, and is thereby admirably adapted for being thrown entirely out of the gun in the act of extraction. The anvil d is composed of a separate piece of metal, and is set on edge crosswise of the recess c, as shown in Figs. 2, 3, and 4, and it is secured in place by forcing down over its ends a small portion of the metal from the inner walls of the recess, as shown in Fig. 4, this being done by a suitable punch, which is forced into the recess for the purpose of "sizing" or finishing the recess for the reception of the primer, which is inserted behind the anvil, but not shown in the drawing, it being a common method of priming this class of cartridges. The object of this sizing operation is to make the recess of the exact

size required to receive the primer, and at the same time to insure a perfect mechanical fit, so as to render it gas-tight when exploded. There is a hole through the bottom of the recess or battery-cup, and also through the cup *a*, for the passage of the flame from the primer to the powder, as shown in the drawings.

An advantage of this manner of re-enforcing the head is, that the disk *b*, when thus forced into its place, serves as a support, not only for the head of the shell, but it also supports the walls of the battery-cup or recess *c*, and thus prevents the latter from being distended by the pressure of the gases within it, whereby the cartridge is rendered more perfectly gas-tight, especially when reloaded and fired many times, as those used in shot-guns are intended to be.

By using the cylindrical shell in a taper

chamber, it will be seen that the shell can be more readily inserted; also any particles of dirt that may chance to be in the chamber not preventing the shell from entering, as it would if both shell and chamber were of uniform diameter and shape.

Having thus described my invention, what I claim is—

A cartridge-shell consisting of the body *B*, having an external cup, *c*, formed in its head to receive the primer, with the internal re-enforce *b* filling the space between the walls of the body and the primer-cup, and the gas check or cup *a* resting thereon, all substantially as described:

W. S. SMOOT.
